Primary Examiner — John Windmuller*Assistant Examiner* — Steven J Czyz(74) *Attorney, Agent, or Firm* — Jingming (James) Cai; SAC Attorneys LLP(57) **CLAIM**

The ornamental design for an outdoor umbrella handle, as shown and described.

DESCRIPTION

FIG. 1 is a front perspective view of an outdoor umbrella handle;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom view thereof.

Portions of the outdoor umbrella handle are shown broken away to indicate that they have no particular length beyond what is shown.

The broken lines depict portions of the article that form no part of the claimed design.

1 Claim, 7 Drawing Sheets(56)
